UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT BREAKER.

Application filed December 2, 1922. Serial No. 604,492.

My invention relates to circuit interrupters, more particularly to those of the fluid type having receptacles containing fluid and on which covers are mounted.

5 One object of my invention is to provide a circuit interrupter with quickly detachable means for permitting ready removal of the several component parts.

10 Another object of my invention is to provide a circuit interrupter in which the number of operations required to remove the tank from the cover is materially reduced.

15 A further object of my invention is to provide a circuit interrupter in which the clamping means are actuated in groups.

In circuit interrupters, as heretofore constructed, it has been customary to provide a large number of bolts passing through flanges on the tanks and holes in the covers. In order 20 to remove the cover from a circuit interrupter of the type just mentioned, it has heretofore been necessary to remove each of the bolts individually before the cover and the tank could be separated. By my invention, it is 25 only necessary to unscrew a relatively small number of suitable connecting means, such as bolts, which control a plurality of readily detachable clamping means to effect the desired separation.

30 Figure 1 is a side view of a circuit interrupter showing an embodiment of my invention.

Fig. 2 is a plan view thereof.

In the several figures of the drawing, the 35 same reference numerals refer to like parts. In the preferred form of my invention, a circuit interrupter 1 comprises a cover 2 and a receptacle or tank 3. A plurality of electrical conductors 4 pass through the cover 2 in 40 any conventional manner. A mechanism 5 is provided for the mechanical operation of the circuit interrupter. These parts may be of any conventional type as they form no part of this invention.

45 The tank 3 is equipped with a flange 4^a which extends beyond the normal circumference thereof and terminates in a plurality of upstanding projections or ears 6. If desired, the flange 4^a may terminate in a substantially rectilinear surface.

50 Cover 2 is equipped with a plurality of bosses 7 and ears 8 which are in alinement with each other and with the ears 6 mounted

on the tank 3. Pivot pins 9 extend through the ears 8 and terminate in the bosses 7, as is 55 shown by the dotted lines in Fig. 2.

Each of the pins 9 is adapted to support a lever 11. As is shown in Fig. 1, the levers 11 are adapted to face outwardly and each comprises an arm extending outwardly from 60 the pivotal support 9 and is provided at its end with means for securing an actuating mechanism, hereinafter described. Extending at an angle to the main part of the lever 11 is another arm or latch 12 which is adapted 65 to engage a suitable recess formed in the corresponding ear 6.

The free end of one of the levers 11 is provided with a bifurcated head 13 for the reception of a securing member 14, such for example, as a threaded bolt. The corresponding end of the adjacent lever 11 is provided with a head 15 which is adapted to anchor, in any suitable manner, the second end of the member 14. 75

In the operation of a circuit interrupter equipped with my invention, the cover 2 and tank 3 are brought into juxtaposition by any suitable means. The corresponding ears 6 and 8 and the boss 7 are in alinement. Securing means 14, which have been previously secured to their respective anchorages 15, are then seated in the bifurcated heads 13. The parts 13 and 15 are then drawn toward each other by the members 14 and suitable cooperating means, such as nuts 16. As the nuts 16 are turned on the members 14, the levers 11 are moved toward each other upon their pivots 9 until the extensions 12 enter the corresponding recesses in the ears 6 and exert an 90 upwardly directed force upon the flanges 4 and tank 3. Movement of the nuts 16 is continued until a tight fit is had between the flange 4 and the cover 2. 80

The weight of tank 3 is sustained entirely 95 by the pressure exerted by arms 12 on the ears 6. Any tendency which the levers 11 have to turn about their pivots 9 and drop the tank is resisted by the tension in the members 14, anchorages 15, nuts 16 and heads 13. By providing a pair of clamps as is clearly shown in Fig. 2, for each circuit interrupter, all other clamping mechanism between the cover 2 and the tank 3 is rendered unnecessary. 100

In dismantling a circuit interrupter 105 equipped with my invention, it is only neces-

sary to unscrew the pair of nuts 16, for the reason that the weight of the tank 3, bearing upon the arms 12 of the several levers, creates a turning movement of these levers as slack 5 is given to them by the loosening of connectors 14 until the arms 12 have turned free from the ears 6. The tank then being entirely free from the cover 2.

By my invention, I have reduced the number of parts which have heretofore been necessary for securing a cover to the tank of a circuit interrupter and, at the same time, greater ease and rapidity are obtained in releasing the relatively movable parts of the 15 circuit interrupter.

It is to be understood that the term "circuit interrupter," as hereinbefore employed, is considered to include all forms of apparatus in which a plurality of relatively movable members are normally adapted to be clamped together.

While I have shown a preferred form of my invention, I do not wish to be limited to the specific structure illustrated, as various 25 modifications may be made therein, within the spirit and scope of my invention, as set forth in the appended claims.

I claim as my invention:

1. In a latching mechanism, a pair of relatively movable members and quickly detachable means for securing said members together comprising a pair of pivoted levers and means for simultaneously operating said levers, said means comprising a connecting 35 member having a threaded portion and a nut in contact with the threaded portion of said connecting member and one of said levers.

2. In an electrical device, a pair of relatively movable members, means for securing 40 said members together comprising recessed elements secured to one of said members, and a pair of pivoted members mounted on the other member and having projections for engaging the recesses in said elements, and 45 means co-operating with a pair of said levers, said means comprising a member anchored to one of said levers and having adjustable restraining co-operation with the other lever for simultaneously causing engagement between the projections carried thereby and 50 their associated recesses.

3. The combination with a receivable mem-

ber and a cover member therefor, of a pair of levers pivoted to one of the members and having a latch for engaging the other member and forcing the members into closed relation and an operating member for the levers pivoted to the free end of one only of the levers and adjustably and detachably engaging the free end of the other lever for moving the 60 levers into locking position.

4. The combination with a receivable member and a cover member therefor, of a pair of levers pivoted to one of the members and having a latch for engaging the other member and forcing the members into closed relation and an operating rod for the levers pivoted at one end to one of the levers and adjustably engaging the free end of the other lever for moving the levers into locking position.

5. The combination with a receivable member and a cover member therefor, of a pair of levers pivoted to one of the members and having a latch for engaging the other member and forcing the members into closed relation and an operating rod for the levers pivoted at one end to one of the levers and detachably engaging the free end of the other lever for moving the levers into locking position.

6. The combination with a receivable member and a cover member therefor, of a pair of levers pivoted to one of the members and having a latch for engaging the other member, the free end of one of the members being provided with a threaded bolt pivoted thereto and the free end of the other levers being bifurcated to receive the threaded end of the bolt and a threaded nut for the bolt for moving the levers into locking position.

7. The combination with a receivable member and a cover member therefor, of a pair of levers pivoted to one of the members and having a latch for engaging the other member, the free end of one of the members being provided with a clamping member pivotally attached thereto and the free end of the other lever being bifurcated to receive the clamping member.

In testimony whereof, I have hereunto subscribed my name this 27th day of November 1922.

CHRISTIAN AALBORG.
